UNITED STATES PATENT OFFICE

ERTHOLD C. JANKE, OF MILWAUKEE, WISCONSIN, ASSIGNOR TO JAYEM MANUFACTURING COMPANY, OF MILWAUKEE, WISCONSIN, A CORPORATION OF WISCONSIN

SHOE

Application filed April 4, 1924. Serial No. 704,191.

The invention relates to shoes, and more particularly to the fastening means therefor.

The lacing of the ordinary shoe permits it to be fitted snugly on the foot, but considerable time is required for putting on and removing the shoe, which is undesirable under circumstances demanding that the time required for this manipulation be minimized.

It is an object of this invention to provide a shoe with a rapidly operated fastening means adjacent the lacing whereby the shoe may be properly fitted on the foot and thereafter may be removed and replaced on the foot by the manipulation of the fastener alone, the lacing remaining in its initially adjusted condition.

The invention further consists in the several features hereinafter set forth and more particularly defined by claims at the conclusion hereof.

In the drawings: Fig. 1 is a perspective view of a shoe embodying the invention showing the fastening means closed;

Fig. 2 is a similar view showing the fastening means opened;

Fig. 3 is a transverse sectional view of the shoe looking forward, the fastening means being closed;

Fig. 4 is a fragmentary sectional view, showing a modified attachment for the fastening means; and

Fig. 5 is a fragmentary view of the fastening device.

In the drawings 10 indicates a shoe, preferably of the blucher type, in which the upper 11 is provided at its forward parted portion with pairs of opposite eyelets 12 for a crossed front lacing 13. Adjacent each side of the lacing portion of the shoe the upper 40 is provided with narrow openings 14 extending substantially parallel to the free forward edges of the upper and reaching the top edge, thus affording narrow ribbon portions in which the eyelets 12 are placed.

The fastener employed for closing the openings is of the multiple operated separable type, a well known variety being illustrated, in which flexible stringers 15 of fabric or leather attached to the upper at the edges 50 of the openings 14 are provided with inter-

locking members 16 secured thereto in alternate relation. The interlocking members are engaged and released by a runner 17 which serves to spread the members to permit their meshing or withdrawal. The runner is conveniently provided with a tab 18 to afford a fingerhold whereby the runner may be moved up to effect a closure and down to release the interlocking members.

The stringers may be secured to either the inside or outside surfaces of the upper, and in the latter case, as illustrated in Fig. 4, the opening 14 presents a groove in which the runner may be moved without pressing into the foot.

The shoe is provided with a gusset 19 attached to the vamp 20 and to the upper in order to avoid entrance of dirt through the laced portion of the shoe. The gusset is provided with folds 21 on either side extending beneath the fasteners to prevent chafing of the foot by the metal parts.

Instead of having fasteners on both sides of the laced portion of the shoe, as illustrated, a fastener on one side only will be sufficient in many instances to afford an opening large enough to receive the foot.

The shoe of this invention is first placed on the foot with the separable fasteners closed and the lacing open, whereupon the lacing is adjusted to obtain the proper fit and then tied. As the lacing 13 is disposed centrally of the forward portion of the shoe, the symmetry and appearance of the shoe will not be impaired by variations in the width of the foot in the shoe, and the term front lacing, as hereinafter noted, defines a lacing in such position. For subsequent removal of the shoe the runners 17 are moved downwardly to release the interlocking members 16, whereupon the laced portion of the upper with its attached gusset is swung outwardly from the rest of the upper to afford an easy removal of the shoe. Thereafter the shoe is placed on the foot with the separable fasteners opened, and it is then only necessary to pull up the runners to effect a closure of the upper, which requires but very little time, the lacing remaining in its initially adjusted condition to insure a properly fitting shoe.

The fastener secured on the inside quarter of the shoe has its lower end disposed substantially in line with the highest portion of the instep. It thus affords the largest possible opening for the insertion of the foot into the shoe and permits this fastener to be used alone without need for manipulating the fastener on the other side.

The term "shoe" as herein used includes 10 a boot.

What I claim as new and desire to secure by Letters Patent is:

1. In a shoe, the combination with an upper having a crossed front lacing for adjusting the shoe to the foot, of a flexible multiple 15 operated separable fastener secured to said upper adjacent each side of said lacing but spaced therefrom and adapted for effecting rapid opening and closure of said upper after 20 initial adjustment of said lacing and without further manipulation of said lacing.

2. In a shoe, the combination with an upper having a crossed front lacing for adjusting the shoe to the foot, of a flexible multiple 25 operated separable fastener secured to said upper adjacent each side of said lacing but spaced therefrom and adapted for effecting rapid opening and closure of said upper after 30 initial adjustment of said lacing, and a gusset secured within said upper and extending beneath said lacing and fasteners.

3. A shoe having the customary medially located front opening and a lace therefor, 35 said shoe also having side slit openings located one beyond each side of the front opening and spaced at equal distance therefrom, whereby the shoe is provided with a trinity of openings symmetrically arranged with relation to the vertical median plane of the 40 shoe, and quick acting fasteners each having a pair of cooperating side members sewed to respective edges of the side slit openings to reinforce the upper adjacent said slits.

4. In a shoe, the combination of an upper 45 having its quarters spaced along their forward edges and bridged by a medially disposed crossed front lacing for initially adjusting the shoe to the foot, there being a slot in one quarter extending adjacent and substantially parallel to the forward edge 50 of said quarter and terminating at its lower end adjacent the lower end of said lacing, and a flexible slide-controlled fastener separably connecting said quarter along said slot and serving as the normal fastening means 55 for the shoe.

5. In a shoe, the combination of an upper having its quarters spaced along their forward edges to form a medially disposed front 60 opening, and one of said quarters having a slot extending adjacent and substantially parallel to the forward edge of the quarter to form a ribbon portion terminating at its lower end adjacent the lower end of said front opening, eyelets secured in said ribbon 65

portion, corresponding opposite eyelets secured in the forward edge portion of the other quarter of said upper, a crossed front lacing passing through said eyelets and bridging the spaced quarters of the upper 70 for initially adjusting the shoe to the foot, and a flexible slide-controlled fastener separably connecting the upper along substantially the entire length of said slot and serving as the normal fastening means for the 75 shoe.

6. In a shoe, the combination of an upper having its quarters spaced along their forward portions to present a medially disposed front opening and to form flaps which at 80 their lower adjacent corner portions are unattached to the shoe, a crossed front lacing joining said flaps for initially adjusting the shoe to the foot, there being a slot in the flap of one quarter extending adjacent and substantially parallel to the forward edge 85 of the flap and terminating at its lower end adjacent the lower end of the flap, and a flexible slide-controlled fastener separably connecting said quarter along said slot and 90 serving as the normal fastening means for the shoe.

7. The combination, with a shoe having an upper provided with the usual row of eyelets along each edge of its front opening and having a slot in its inner quarter disposed in substantially parallel adjacent relation to said front opening and terminating at its lower end substantially in line with the highest point of the instep and opening at its upper end in the upper edge of the quarter, a front central lacing received in said eyelets and bridging the front opening of the upper, and slide-controlled means connecting said upper together along said slot and having its lower terminus substantially in line with the highest point of the instep at the first metatarsal bone.

8. In a boot, the combination of an upper having its quarters spaced along their forward edges to form a front opening, a medially disposed crossed front lacing bridging the forward edge portions of said quarters for initially adjusting the boot to the foot, there being a slot in the inner quarter of the upper extending adjacent and substantially parallel to the forward edge of said upper and terminating at its lower end adjacent the lower end of said lacing, and a flexible slide-controlled fastener separably connecting said inner quarter along said slot to serve as the normal fastening means for the boot, and said fastener having its lower terminus substantially in line with the highest part of the instep at the region of the first metatarsal bone when the foot is in the boot, whereby to facilitate the insertion of the foot into the boot and the removal of the foot therefrom.

In testimony whereof, I affix my signature.
ERTHOLD C. JANKE.
